CLAIM

The ornamental design for an enclosure for electronic equipment, as shown and described.

DESCRIPTION

FIG. 1 is a front elevational view of an enclosure for electronic equipment showing our new design;

FIG. 2 is a rear elevational view thereof;

FIG. 3 is a right side elevational view thereof;

FIG. 4 is a left side elevational view thereof;

FIG. 5 is a bottom plan view thereof;

FIG. 6 is a top plan view thereof;

FIG. 7 is a front and upper right perspective view of the enclosure for electronic equipment shown on an enlarged scale;

FIG. 8 is a front and upper right perspective view thereof shown with the front door in the open position; and,

FIG. 9 is a front and upper right perspective view thereof shown with the front and rear doors in the open position.
